UNITED STATES PATENT OFFICE

2,246,204

APPARATUS FOR MAKING PORTIONS OF SINKS

Vincent J. Graf, Detroit, Mich., assignor, by mesne assignments, to Steel Plumbing Wares, Inc., Detroit, Mich., a corporation of Michigan

Original application August 25, 1933, Serial No. 686,796. Divided and this application December 13, 1937, Serial No. 179,388

2 Claims. (Cl. 113—49)

This invention relates to sinks or washbasins formed by stamping or draw die operations, and to an apparatus for producing the same, and particularly, although not exclusively, to the formation from a single sheet or blank of metal of a sink of that character or design preferably having a basin, a single or double drainboard terminating in a depending apron flange, and an upright flanged back wall or splashboard.

This application is a division of my co-pending application Serial No. 686,796, filed August 25, 1933.

An object of the invention is to provide an apparatus for pressing or drawing the entire sink from a single blank of metal while at the same time producing around the edge of the back wall or splashboard a continuous flange which merges integrally and co-extensively with the apron flange.

Another object of the invention is to provide an apparatus capable of forming from a single metal sheet a basin, apron flange and flanged splashboard with continuous, uninterrupted metal surfaces free from welded slits or patches, thereby securing substantial economies in manufacture and improved appearance, while eliminating enameling flaws resulting from the difficulty in providing a clear, uniform, baked enamel surface due to welds in the foundation metal.

A further object is to provide an apparatus capable of producing a rolled or turned marginal rim between the basin and apron flange and one which will join the rim to the upright splashboard or back panel by increasing the metal area at the juncture thereof.

Other objects of this invention will appear in the following description and appended claims, reference being had to the accompanying drawings forming a part of this specification wherein like reference characters designate corresponding parts in the several views.

Fig. 1 is a perspective view of a finished sink made in accordance with the invention.

Fig. 2 is a vertical longitudinal section of the die members for forming the basin portion of the sink.

Fig. 3 is a perspective view of the blank as formed by the dies of Fig. 2.

Fig. 4 is a vertical transverse section of the die mechanism for preliminarily forming the splashboard of the sink.

Fig. 5 is a perspective view of the blank as formed by the mechanism of Fig. 4.

Fig. 6 is a longitudinal vertical sectional view

illustrating the mechanism for reforming the basin portion and further fabricating the blank.

Fig. 7 is a perspective view of the blank formed in the mechanism of Fig. 6.

Fig. 8 is a vertical transverse section of the mechanism for further formation of the splashboard of the sink.

Fig. 9 is a perspective view of the sink after it issues from the mechanism of Fig. 8.

Fig. 10 is a vertical transverse section illustrating the mechanism for flanging the splashboard.

Fig. 11 is a perspective view of the blank as it appears after the operation performed by the mechanism of Fig. 10.

Fig. 12 is a fragmentary vertical transverse section illustrating the next operation of fabricating the sink.

Fig. 13 is a perspective view of the sink as it appears after the operation performed by the mechanism of Fig. 12.

Fig. 14 is a fragmentary vertical transverse section of the mechanism for trimming the bottom flange of the sink.

Fig. 15 is a fragmentary perspective view of the sink after the trimming operation of Fig. 14.

Fig. 16 is a fragmentary section of the mechanism for trimming the top and side flanges of the sink.

Fig. 17 is a fragmentary perspective view of the sink after the operation performed in Fig. 16.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the claimed invention herein beyond the requirements of the prior art.

In accordance with the invention there is formed from a single metal blank or sheet, a sink which may either be of the double or single drainboard type or simply a basin type, having a continuous depending apron flange extending around the front and sides, and an upstanding back panel or splashboard which is rearwardly flanged along the top and ends thereof, the lower part of the end flanges of the splashboard continuing into the rear portions of the apron flange. Heretofore, where it has been attempted to fabricate sinks of this character from sheet metal it has

been necessary to slit or cut away a part of the metal at the juncture of the splashboard and the rolled edge or rim of the basin or of the drainboard, as the case may be. Moreover, in accordance with previous practice it has been necessary to close these slitted edges by welding. Furthermore, the fabrication of such sinks according to previous practice has resulted in leaving gaps between the rear edges of the apron and the splashboard flanges, and these gaps have been filled in by metal patches welded in position. Thus, it will be noted that previous practice has necessitated either slitting or patching, or both, and the consequent welding of the metal at such points. Such practice has not only introduced expensive operations but has rendered it difficult if not impossible to produce a final product of satisfactory appearance. This is particularly true where the formed article is provided with a surface finish of enamel, it having been found in practice that blemishes or imperfections appear in the enameled surfaces at points where welding has taken place.

In the drawings there is illustrated an apparatus for performing a succession of different steps by which a sink of the double drainboard type may be formed from a single metal sheet or blank free from welded joints and patches. It will be understood, of course, that the apparatus is equally applicable to the formation of a single drainboard sink, and in fact of a sink without a drainboard wherein the structure comprises a fluid basin, an upright back or splashboard and a continuous apron flange extending around the front and sides of the basin and merging with the flanged ends of the splashboard.

In Fig. 2 I have shown the mechanism for forming the basin portion B of the sink or wash-basin. A single sheet or blank of metal A is placed in position in a die which, for convenience, is shown in closed position. This die is used in a toggle or double acting sheet metal drawing press, shown as a 24. The die comprises a punch 25, a lower die ring 26, and an upper die member or hold-down ring 27 which binds the metal sheet or blank in position between the die members so that the punch can draw the metal to provide the basin portion B. The blank issues from the apparatus of Fig. 2 in the form in which it is shown in Fig. 3.

The next operation is that of preliminarily forming the splashboard or back portion C. This operation is performed in a die, shown in closed position, which is used in a single acting sheet metal bending press 28, provided with an air cushion under the bed of the press and pins 29 extending through the press bed and lower die member 30 with their upper ends engaging the pad or binder plate 31 to hold the metal sheet or blank A flat when forming. The broken lines AA show the metal before the operation is completed. A punch or male member 32 is provided for forming the splashboard portion C. This punch is actuated from the ram of the press (not shown). A punch pad or upper binder plate 33 is used to hold the metal in position. The pins 29 serve to apply pressure from the air cushion, located in the bed of the press, to raise the pad 31 above the die member 30 to hold the metal sheet securely between the pad 31 and the punch 32. In Fig. 5 I have shown the partially fabricated blank as it issues from the apparatus of Fig. 4.

In Fig. 6 there is shown a die for performing the second drawing operation on basin B and for

forming the drainboard D and drainboard beads. The die is shown in closed position and is used in a toggle or double-acting drawing press. The broken lines AA show the shape of the metal before the instant operation is performed. A portion of the press is shown at 34, the ram of which actuates a punch 35. 36 represents an interchangeable drainboard punch or male units which are integral with the punch 35. A lower die member 37 cooperates with the punch 36 to redraw the basin and form the drainboard and drainboard beads. Interchangeable units 38 are provided so that either a single drainboard and beads or a double drainboard and beads may be formed in the press. A portion of the die for striking the shape on the bottom of the sink basin is shown at 39. Any suitable means, such as guides 40, may be employed for ensuring the proper locating of the indexing parts of the die. The hold-down ring binder plate or upper die member 41 binds the metal in place between it and the lower die ring 37, and thus holds the sheet metal from wrinkling or buckling when the drainboard and beads are being formed.

Fig. 7 shows the blank after completion of the operation performed by the mechanism of Fig. 6.

In Fig. 8 the die is shown in closed position, which die performs the second operation on the splashboard C. 42 designates a punch for forming the splashboard, the latter being bent from its horizontal position shown in broken lines at CC, to the vertical full-line position C between the punch 42 and a die member 43, the latter being fastened to the bed of the press. 44 is a punch pad or upper binder plate which holds the metal in position. During the operation in the press of Fig. 8, a punch or steel section 45 is employed to restrike the radius at the end of the sink to form the beads or embossed portions E, see Fig. 9, sufficient metal being introduced at these points to provide, in a succeeding operation, the proper radius of curvature at the juncture of the rolled rim and upright back wall or splashboard.

Fig. 9 shows the blank after it issues from the mechanism of Fig. 8.

In Fig. 10 there is shown a mechanism for embossing the face of the splashboard and for forming flanges on the top and ends of said splashboard. This mechanism also comprises a punch or male form 45a which is actuated from the ram of the press and cooperates with a die 46 to form the top and end flanges on the splashboard C. A hold-down ring or binder plate 47 binds the metal in the space between it and the die 46 to hold it from wrinkling or buckling when forming. A die pad or die insert 48 is actuated by and yieldably held in position by pressure pins 49 and serves to hold the metal between itself and the punch 45a. The die pad 48 carries a steel embossing member or die block 50 which is held within a recess in the upper face of the die pad 48. Downward movement of the punch against the die insert 48 causes the die block 50 to emboss the splash panel at C³. Pressure pins 51 engage the embossing member 50 so that when the die pad 48 moves down to a given point the pins 51 will project the embossing member 50 into the position shown in Figure 10 to form in cooperation with the die 45a the embossed panel C³. Thus, the mechanism of Fig. 10 produces the top flange C' and the side or end flanges C² as well as the embossed panel C³, as shown by Fig. 11.

It will be noted that in the operations per-

formed by the mechanisms of Figs. 8 and 10, the back panel C is formed with a continuous flange and the marginal area F of the front section is formed into a continuous apron flange merging into the back wall flanging. In accomplishing this the marginal metal of the back or splashboard is pressed rearwardly substantially along the line G (Fig. 9). The integrally joined metal areas H and I are simultaneously drawn or pressed rearwardly in the same direction, while at the same time the metal areas indicated at F and C are held in fixed position between the co-operating die members.

The draw operation is shown in Fig. 10 and the result thereof is illustrated in Fig. 11, wherein the back or splash-panel C is provided with a continuous uninterrupted flange along the top edge at C' and downwardly above the end or side edges at C², the flange portions C² merging into a horizontal area J, the metal of which is drawn largely from the area I shown in Fig. 9. The direction of the draw producing the areas C', C² and J is illustrated by the arrows in Fig. 11, and the shape of the blank at this stage is also substantially illustrated in this figure. Although a part of the metal during the draw may remain in the form of a web K, this portion may be readily removed in the final trim operations.

In Fig. 12 there is shown mechanism for drawing the apron flange E of the sink and for embossing the drain opening in the basin B. A die construction is shown which comprises a lower die ring or member 52, a punch or male form 53, a hold-down ring or binder 54, and a die plate 55, which latter is fastened to die ring 52. The member 55 serves as a rest for pad 56, binder plate 57 and forming punch 58. The punch 58 forms the drain emboss in the sink basin B and is secured to the die plate 55. Pressure pins 60 serve to apply pressure from air cushions (not shown) in the bed of the press and to raise the die pad 56 and binder plate 57 above the die ring 52, thus to hold the sheet metal sink A securely between the plate 57 and the punch or male form 53 before forming. As the press closes and the die members move relatively to one another the die ring 52 wipes the apron portion E of the sink from its horizontal position shown in broken lines at EE to the upright position shown in full lines. The result of this operation is the sink shown in Fig. 13 which has the apron E extending continuously around the front and sides or ends thereof. Thus the rear portions of the apron flange E form integral continuations of the splashboard end flanges C².

The next two operations are performed by the mechanism shown in Figs. 14 and 16. These are the trimming of the front and sides of the apron flange E as shown in Fig. 14 and the trimming of the top and sides of the splashboard C, as shown by Fig. 16. Each figure shows a cam die in closed position, to be used in a single acting sheet bending press. The ram 61 of the press carries a cam driver or wedge 62 which actuates a die cam 63, the die cam containing steel trimming sections or cutters 64, and being supported by a die shoe 65. The die shoe serves as a carrier for the die cam 63 and is fastened to the bed of the press. A spring tensioned cam pad or binder plate 66 holds the sink A in proper position for the trimming operation. The gauge or support for locating the apron is shown at 67 in Fig. 14, whereas the gauge or locator for the splashboard is shown at 68 in Fig. 16. After the apron flanges have been trimmed in Fig. 14, the sink is transferred to

the position in which it is shown in Fig. 16 and the flanges of the splashboard are trimmed. Figs. 15 and 17 show the sink after it issues from the respective trimming operations.

After the foregoing operations of trimming around the edges of the apron flanges and the flanges of the upright splashback or panel, the sink may be introduced into a suitable press or presses provided with mechanism for flanging the bottom edges of the front and sides of the apron E and also for flanging the edges of the top and sides or ends of the splashboard or panel C. Also the sink may be operated on by suitable mechanism for piercing the metal to form the drain hole or opening in the bottom of basin B. The flanging mechanism and drain hole piercing mechanism may be constructed in accordance with my aforesaid co-pending application.

In the present embodiment herein illustrated, I have set forth an apparatus for forming a sink or washbasin from a single piece of sheet metal. The invention, however, is not limited to the sequence of operations performed by the apparatus shown, nor is it limited to the particular form or type of apparatus shown since, obviously, the mechanism of certain figures of the drawings may be combined or rearranged in any desired order or sequence.

If desired the back or splashboard panel and the basin or drainboard panel may first be formed, after which the basin and the drainboard proper may be pressed out. In some instances the drainboard or apron flange will be omitted, and in such case it will be understood that the rolled rim T will form the upper margin of the basin proper. Considered from one aspect the invention contemplates (1) forming a substantially horizontal basin panel and a back or splashboard panel substantially at right angles thereto, (2) rearwardly upsetting or drawing the metal at each end of the back panel to produce a vertical end flange on the back panel and a co-extensive horizontal extension of the marginal portion of the basin panel, and (3) downwardly drawing or pressing said marginal portion and extension to provide a continuous apron flange terminating at its rear edge substantially in line with the rear vertical edge of the back panel flange.

It will also be understood that the invention may be carried out by first stamping the blank or sheet to produce the horizontal basin panel and the upright or vertical splashboard panel; second, drawing the marginal portions of the basin panel downwardly to provide a continuous apron around three sides thereof, and third, rearwardly flanging the back panel or splashboard around its three edges and drawing the metal at the juncture of the back panel and apron to increase the metal area so as to form the end flange of the back panel with an extension of the apron.

Thus, it will be seen that the invention, in one of its broader aspects, contemplates forming a single metal blank or sheet by pressing or drawing operations, through suitable dies and blank holders, to produce a horizontal panel or section having a basin incorporated therein either with or without a drainboard or drainboards, a continuous integral apron flange extending around three sides of the horizontal panel, a substantially vertical back panel or splashboard continuously flanged around its three edges; and drawing the metal at or near the juncture of the back panel and apron (see Figs. 10 and 11) to introduce into

the apron at the rear edges thereof integral extensions of the back panel flanging.

I claim:

1. In an apparatus for forming portions of a sink from a single preformed metal blank embodying a basin, a laterally projecting apron forming portion and an upright back panel; mechanism for forming a continuous uninterrupted rearwardly projecting flange along the upper and end marginal edges of said back panel, comprising cooperating die portions for pressing rearwardly the upper edge portion of the back panel and cooperating die portions for simultaneously pressing rearwardly the upright end portions of said back panel to form rearward extensions of the apron forming portion integral with the rearward marginal flanging of the back panel.

2. In an apparatus for forming portions of a

sink from a single preformed metal blank embodying a basin, a laterally projecting apron forming portion and an upright back panel; mechanism for forming a continuous uninterrupted rearwardly projecting flange along the upper and end marginal edges of said back panel, comprising cooperating die portions for pressing rearwardly the upper edge portion of the back panel and cooperating die portions for simultaneously pressing rearwardly the upright end portions of said back panel to form rearward extensions of the apron forming portion integral with the rearward marginal flanging of the back panel, and a member cooperating with one of said die portions for simultaneously forming an embossed panel located within the area of said back panel.

VINCENT J. GRAF.
